UNITED STATES PATENT OFFICE.

GASTON A. BRONDER, OF BROOKLYN, NEW YORK; LUCIA R. BRONDER, ADMINISTRATRIX OF SAID GASTON A. BRONDER, DECEASED, ASSIGNOR OF ONE-HALF TO THOMAS COSTIGAN, OF NEW YORK, N. Y.

POWER DECLINKERING APPARATUS FOR GAS GENERATORS.

Application filed August 11, 1920. Serial No. 402,877.

To all whom it may concern:

Be it known that I, GASTON A. BRONDER, citizen of the United States, and resident of the borough of Brooklyn, city of New York, in the county of Kings and State of New York, have invented certain new and useful Improvements in a Power Declinkering Apparatus for Gas Generators, of which the following is a specification.

This invention relates to a power declinkering apparatus which is particularly adapted to remove clinkers from a gas generator furnace.

The organization of the invention comprises a reciprocating declinkering bar which is slidably supported in a pair of guides. The declinkering bar operates through the charging opening of the roof of the generator and during its reciprocations is maintained at times in a vertical plane and at other times in a plane inclined to a vertical plane. The guides are pivoted in a saddle to swing in a vertical plane and the saddle in turn is pivoted to a guide ring to swing in a vertical plane at right angles to the first plane. The guide ring is rotatably supported on the mouth piece of the furnace of the generator. An engine is provided which raises the declinkering bar and permits it to drop by gravity. The striking end of the bar is directed against the clinkers that form in the generator and by means of its tipping and revolving functions and its adaptability to operate at different levels, the clinkers can be broken and removed from the generator throughout any portion thereof.

In the accompanying drawings Fig. 1 represents a side elevation of the apparatus with its appurtenances and a vertical axial section of a gas generator; Fig. 2 shows a front view of the declinkering bar with its immediate appurtenances; Fig. 3 represents a right hand side view of Fig. 2; Fig. 4 shows a rear view of Fig. 2; Fig. 5 represents a side view of the declinkering bar with a fragmentary portion in vertical longitudinal section; Fig. 6 shows a left hand side view of Fig. 5; Fig. 6a shows a longitudinal fragmentary section of the striking end of a modified declinkering bar; Fig. 6b represents a section of Fig. 3 on the line 6b—6b; Fig. 7 is an enlarged section of Fig. 3 on the line 7—7; Fig. 8 shows an enlarged

section of Fig. 3 on the line 8—8; Fig. 9 shows an enlarged section of Fig. 3 on the line 9—9; Fig. 10 represents an enlarged top plan view of a guide ring of the apparatus with its appurtenances and Fig. 11 is a section of Fig. 10 on the line 11—11.

A gas generator furnace is indicated with the side wall 20 and the roof 21 having the charging opening 22. A grate 23 has located thereon the fuel 24 and clinkers 25 are also indicated in the generator. A mouth piece 26 has connected thereto an extension 27 which latter is fitted in the opening 22. A detachable projecting ring 27a is located upon the upper face of the mouthpiece 26.

An upper beam 28 has extending therefrom journal brackets 28a for the guide sheaves 29. Floor beams 30 with the flooring 31 are located over the generator.

The declinkering apparatus comprises the guide ring designated in its entirety by the letter A, which is rotatably supported upon the mouth piece 26. An oscillating saddle B is pivoted to the guide ring A. A pair of bar guides C are in turn pivoted to the oscillating saddle B and the declinkering bar D is slidably supported in the bar guides C. An engine E controls a wire rope F which in turn actuates the declinkering bar D.

The guide ring A comprises the hexagonal frame of angular cross section with the vertical flange 35 and the horizontal flange 36. Journal cages 37 are formed with the flange 35 and have journaled therein the carrying rollers 38. Guide pins 39 extend from the lower face of the horizontal flange 36. A roller bracket 40 is fastened to the upper face of the horizontal flange 36 and has journaled therein the guide roller 41. A journal lug 42 is formed with the flange 36. The saddle B comprises the U-shaped frame having the rear wall 43 and the side walls 44. Each of the latter has formed therein the T-shaped aperture 45 with the upper bearing 45a, the lower bearing 45b and the inlet and outlet passage 45c. A pivot 46 extends from the rear wall 43 and is supported in a bearing formed in the journal lug 42.

The bar guides C comprise the two longitudinal and parallel angle irons 48, which are connected by the connecting plates 49, 50, 51 and 52. One of the angle irons 48 is

extended as shown at 48^a to form a protecting shield for the operator when the declinkering bar D reciprocates. A reinforcing plate 53 is connected to each of the angle irons 48. A pair of trunnions 54 with the shanks 55 extend from about the central portions of the angle irons 48. The said shanks extend through the said angle irons 48 and through the reinforcing plates 53 and are connected to both. A pair of angle iron guides 56 are fastened to the reinforcing plates 53.

At both the top and bottom ends of the angle irons 48 are fastened a pair of roller cages 57, that have journaled therein the side guide rollers 58 having the flanges 59. A pair of angle clips 60 are fastened at both the top and bottom ends of the angle irons 48 and each of said pair have journaled 20 therein the rear guide roller 61.

To one of the angle irons 48 is fastened a bracket 65 which has extending therefrom the rear operating handle 66. To the other angle iron 48 is fastened a bracket 67 similar to 65, which has extending therefrom the side operating handle 68.

To the angle irons 48 are fastened the brackets 69 which have openings 70 for the detachable locking bar 71.

30 The declinkering bar D is shown with the tapered striking end 72. At about the central portion of the bar D is secured a bifurcated lug 73 with the openings 74.

A metallic strap with a pair of members 35 75 has fastened to its lower end the I-plate 76 which latter is hinged to the lug 73 by means of the pin 77.

40 A triangular ring 78 engages the upper connecting portion of the members 75 of the strap and the ring in turn has connected thereto the hoisting rope F.

The engine E is provided with the drum 80 for the rope F. An operating handle 81 permits the engine E to be reversed so as to 45 enable the rotations of the drum 80 to be reversed.

In Fig. 6^a the lower or striking end of the bar D is shown tapered with the longitudinal cone 85, which latter consists of a bar of tool steel or other hard and strong material.

To operate the declinkering apparatus an operator controls the engine E by means of the operating handle 81 to rotate the drum 55 80 in opposite directions, whereby the declinkering bar D is raised by said engine and permitted to drop by gravity. A second operator at the same time is stationed adjacent to the mouth piece 26 and by means of the 60 operating handles 66 and 68 is enabled to tilt the bar D forward and backward and sideways. He is also enabled by said handles to revolve the guide ring A and thereby locate the bar D at any point of the inner cylindrical surface of the generator fur-

nace to detach the clinkers 25 from the wall 20 thereof. It will be noted that by means of the engine the declinkering bar D can be operated at different levels in the furnace.

When the declinkering apparatus is to 70 be removed from the generator the locking bar 71 is located in the openings 70 of the brackets 69 and then by means of the rope F the bar D is raised. When the lug 73 reaches the bar 71 the bar guides C will rise 75 and with it the guide ring A will also be lifted, the trunnions 54 engaging the upper bearings 45^a of the side walls 44 of the saddle B. The inlet and outlet passages 45^c enable the bar guides C to be detached from 80 the guide ring A. After the guide ring A is lifted from the mouth piece 26 the protecting ring 27^a is removed.

Having described my invention what I desire to secure by Letters Patent and 85 claim is:

1. In a power declinkering apparatus for gas generators, the combination of a rotatable guide ring, a pair of guides pivotally supported within the ring, a declinkering bar slidably located in the guides, a strap with one end thereof hinged to the bar, a guide roller journaled in the ring for said strap, and hoisting means connected to said strap. 95

2. In a power declinkering apparatus for gas generators, the combination of a detachable protecting ring located upon the top face of the mouth piece of a generator, a rotatable guide ring supported on the top face of the protecting ring, a pair of guides pivotally supported within the guide ring to swing in two planes with one plane at right angles to the other plane, a reciprocating declinkering bar slidably supported 100 in the guides, a detachable locking bar to lock the bar to said guides, and means to raise the bar and thereby also raise the said guides. 105

3. In a power declinkering apparatus for 110 gas generators, the combination of a rotatable guide ring supported above the top face of the mouth piece of a generator, a saddle pivoted to said ring, said saddle having upper bearings and lower bearings and having 115 an inlet and an outlet passage leading to said bearings, a pair of guides, trunnions extending from said guides adapted to engage either the said upper or lower bearings of the said saddle, said trunnions normally bearing on the lower bearings, a declinkering bar slidably supported in the guides, a detachable locking bar for said guides to lock the declinkering bar to said guides and hoisting means to reciprocate the declinkering bar, when unlocked, said means also enabling the declinkering bar to hoist said guides when said locking bar is in place and the trunnions engaging the upper bearings of the saddle removing the 120 125 130

guide ring from said mouth piece when said bar and guides are being raised.

4. In a power declinkering apparatus for gas generators, the combination of a rotatable guide ring, an oscillating saddle pivoted to the ring, a pair of bar guides hinged to the saddle, a declinkering bar slidably supported in said bar guides, and means to reciprocate the bar in the guides.

10 5. In a power declinkering apparatus for gas generators, the combination of a rotatable guide ring supported above the mouth piece of a generator, a saddle having an aperture with upper bearings and lower 15 bearings pivoted to the ring, a pair of bar guides located within the saddle, a trunnion extending from each bar guide and normally supported in the adjacent lower bearings of the saddle, a declinkering bar slidably 20 guided in the bar guides, a lug fastened to the bar, a strap with its lower end connected to the said lug, a pair of brackets fastened to the bar guides, a detachable locking bar supported in the brackets and means to re- 25

ciprocate the strap and therewith the declinkering bar in the bar guides, said lug on the declinkering bar bearing against said detachable locking bar when the declinkering bar is sufficiently raised in the bar guides 30 when the detachable locking bar is in place, the trunnions of the bar guides simultaneously seating in the upper bearings of the aperture of the saddle and raising the guide ring.

35 6. In a power declinkering apparatus for gas generators, the combination for the mouth piece of a generator of a detachable protecting ring located upon the upper face

thereof, a guide ring, carrying rollers for the guide ring bearing upon said protecting 40 ring, guide pins extending from said guide ring into the mouth piece, a guide roller journaled in one side of the guide ring, a saddle pivoted in the other side of the guide 45 ring, a pair of bar guides hinged to the saddle, a pair of side guide rollers at the top end and also at the bottom end of the bar guides, a rear guide roller at the top 50 end and also at the bottom end of the bar guides, a declinkering bar within the bar guides guided by said rollers and operating handles extending from the declinkering bar.

7. In a power declinkering apparatus for gas generators, the combination of a reciprocating declinkering bar and a pair of guides for the bar, each guide comprising an angle iron and a reinforcing plate, one of 55 said angle irons extended at its upper end to form a protecting shield for the operator of the apparatus.

8. In a power declinkering apparatus for gas generators, the combination of a detachable protecting ring for the upper face of the mouth piece of a generator, a rotatable 60 guide ring supported on the protecting ring, an oscillating saddle pivoted to the guide ring, a pair of guides pivoted to the saddle, a declinkering bar slidably supported in the guides, and an engine to reciprocate the bar. 70

Signed at the borough of Manhattan, city of New York in the county of New York and State of New York this 9th day of August A. D. 1920.

GASTON A. BRONDER.
